Patented June 10, 1919.

UNITED STATES PATENT OFFICE.

JAMES G. BRICKER, OF CLEVELAND, OHIO.

GROUTING-TOOL.

1,306,135.

Specification of Letters Patent. Patented June 10, 1919.

Application filed November 6, 1916. Serial No. 129,790.

To all whom it may concern:

Be it known that I, JAMES G. BRICKER, a citizen of the United States, residing at Cleveland, in the county of Cuyahoga and State of Ohio, have invented certain new and useful Improvements in and Relating to Grouting-Tools, of which the following is a specification.

This invention relates to a grouting tool adapted for spreading material over surfaces covered with stones, bricks, or blocks, whereby the grouting material will be caused to fill the spaces, interstices and crevices between the stones, bricks or blocks. The tool 10 is especially adapted for use in laying of pavements.

One object of the invention is to provide an improved tool which facilitates the operation of spreading material over the paved surfaces.

Another object of the invention is to provide a tool of this character having a flexible operating edge capable of conforming to the surfaces over which a grouting material is to be spread.

Another object of the invention is to provide a tool of this character with a flexible operating edge, whereby relatively high efficiency and speed of operation is attained.

Another object of the invention is to provide a tool of this character with a flexible edge which tends to force the grouting material downwardly into the spaces, crevices or interstices between the paving blocks as the tool is manipulated thereover.

Another object of the invention is to provide a tool of this character with an adjustable section, whereby an effective and efficient operating edge can be maintained at all times.

With these and other objects in view, the invention consists of the parts or combination of parts hereinafter described and set forth in the appended claims.

In the drawings:

Figure 1 is a perspective view of a grouting tool, embodying my invention, a portion of the operating handle therefor being broken away.

Fig. 2 is a top plan view of the tool, the handle being omitted.

Fig. 3 is an end elevation of the parts shown in Fig. 2.

Fig. 4 is a section on the line 4-4 of Fig. 2.

In the drawing, 1 indicates as an entirety

a frame or support to which a section of flexible material 2 is secured. The section of material 2, as shown, extends slightly beyond the lower edge of the support 1, whereby it is adapted to engage with the grouting material and spread the same over the surface being paved or covered with stones, bricks, blocks or similar articles.

The support 1 preferably comprises a pair of rectangular sheet metal plates 1^a, 1^{a'}, which receive between them the section of material 2. The section of material 2 is preferably equal in length to but slightly wider than the plates 1^a, 1^{a'}, so that when it is first placed therein its operating edge will extend the desired distance beyond the lower edges of the plates 1^a, 1^{a'}. The plates 1^a, 1^{a'}, are preferably spaced apart a distance substantially equal to the thickness of the flexible section 2, so as to form a suitable support therefor, maintain its shape as well as to protect the unused portion thereof until it is needed. Any suitable means may be provided for supporting and maintaining the plates 1^a, 1^{a'}, in parallel relationship to each other with the flexible section 2 between them. The improved means which I have shown for illustrative purposes preferably consist of a plurality of members 3. I have preferably provided two supporting members 3 and arranged them near opposite ends of the plates 1^a, 1^{a'}. Each supporting member 3 preferably comprises a pair of arms 3^a, 3^b, extending transversely of and secured, in any well known manner, to the opposite outer faces of the plates 1^a, 1^{a'}, and a connector 3^c which connects the upper ends of the arms 3^a, 3^b, together. The connector 3^c is preferably of annular or loop shape to withstand, without danger of breakage, any force which tends to move the plates 1^a, 1^{a'}, away from or toward each other.

The arms 3^a, 3^b, may be secured to the plates 1^a, 1^{a'}, by counter-sunk screws 3^d. The free ends of the arms 3^a, 3^b, preferably extend substantially to the lower edges of the plates 1^a, 1^{a'}, as shown in Fig. 4.

In the form of construction just described, it will be seen that the space between the plates 1^a, 1^{a'}, is practically open on all sides of the latter, thus providing for the ready removal of an old flexible section 2 and the replacement between the plates of a new section at any time, for the easy and efficient removal of any hardened material that may have accumulated in or about the plates.

4 indicates means for adjustably and detachably securing the flexible section 2 to and between the supporting plates 1^a, 1^{a'}. The means 4 preferably comprise a thumb screw 4^a which fits a screw threaded opening 4^d preferably formed in one of the arms 3^a, 3^b, of each member 3. The screw 4^a is adapted to extend entirely through an opening 4^c, formed in the adjacent plate and 10 registering with the screw-threaded opening 4^d, so that when the screw is tightened, it will engage with the adjacent surface of the flexible section 2 and clamp or secure it against the plate 1^a or 1^{a'} on the opposite 15 side thereof. The securing devices 4 are preferably secured to that arm of the plate supporting member 3 which is secured to the plate carrying the handle, indicated as an entirety at 5. The inner end of each screw 20 4^a is preferably rounded or pointed so that when the screw is tightened against the flexible section 2 it will project slightly thereinto and thus securely position the flexible section relative to the plates 1^a, 1^{a'}. The adjusting screws 4^a preferably extend through 25 and have screw threaded engagement with openings in the arms 3^b so as to provide a relatively long engaging surface for the screws.

30 The handle 5 may be secured to one of the plates 1^a, 1^{a'}, in any suitable manner. For the purpose of illustration I have shown a pair of sheet metal semi-circular members 6, 6, each having a foot 6^a adapted to be riveted 35 or otherwise secured, as shown at 6^b, to the adjacent supporting plate, and a collar 6^c surrounding the members 6, 6. One end of the handle 5 is adapted to be inserted in between the members 6, 6, and clamped there- 40 between by the operation of drawing together the free ends of the collar 6^c. This latter operation may be effected by means of a suitable screw 7, extending through openings formed in the opposite ends of the collar 6^c, and a nut 7^a thereon.

The section of material 2 may be formed from some material which is relatively stiff, but sufficiently flexible to slightly bend or fold rearwardly as the tool is being moved in 50 either direction and at the same time adjust itself to the unevenness of the surface over which the tool is operated. I prefer to use a section of material formed from woven material and rubber, but other materials, 55 such as leather, fabric, canvas and rubber alone may be advantageously used.

The section of material is fixed to the support 1 so that a portion thereof projects a short distance beyond the lower edge of the 60 support. The section of material 2 will extend beyond the lower edge of the support 1 to a greater or lesser extent depending largely upon the flexibility of the material used, the roughness or unevenness of the 65 surface over which the grouting material is to

be spread and in the character and viscosity of the grouting material to be filled in between the stones, bricks or blocks. When the tool is first assembled, the section of flexible material 2 may be slightly greater in size 70 than the plates 1^a, 1^{a'}, as already described. As the exposed or projecting edge of the flexible section 2 wears away, the clamping devices 4 can be unclamped and the section of material 2 moved or adjusted outwardly 75 a sufficient distance to provide a new operating or spreading edge. Such adjustment of the flexible section 2 can be repeated each time a new operating edge is required until the entire section of material is worn away, 80 at which time a new section of material can be positioned between the plates 1^a, 1^{a'}.

By positioning the clamping devices 4 near the lower edge of the plate 1^{a'}, substantially all of the flexible section 2 can be utilized 85 before substituting a new section of material.

The tool is adapted for use in spreading over stones, bricks and blocks, a filler of any desired character. In practice I have found 90 it especially adapted for spreading cement, and mastic and bitulithic materials.

By the provision of a flexible material along the operating edge of the tool, I am enabled to operate the tool effectively 95 and relatively fast since the flexible material readily accommodates itself to any unevenness in the surface being grouted and permits the tool to easily slide thereover. Furthermore, due to the flexibility of the 100 surface engaging edge of the tool, movement of the tool to and fro causes the flexible edge to bend, fold, flex or yield rearwardly so that such edge tends at all times to force or press the grouting material 105 downwardly or toward the surface to be grouted rather than forwardly as is the case in all tools, of which I am aware, heretofore used. The support is correlated with the handle at such an angle as to most 110 effectively spread the grouting material. In operation, the support 1 serves to move the mass of material as it is manipulated by the operative in one direction or the other, while the flexible edge as it bends or flexes serves 115 to force or press the grouting material downwardly into the spaces, crevices and interstices between the blocks, as the tool passes thereover, so that by a few manipulations of the tool over the surface, the spaces, 120 crevices and interstices therein will be entirely filled. It will thus be seen that while the support 1 serves to move or spread the bulk of the material, the flexible operating edge engages that portion of the material 125 adjacent to the surface and presses downwardly into the spaces to be filled. As the flexible operating edge readily accommodates itself to any roughness or unevenness in the surface, the action thereof will be 130

most efficient, thus making it possible to utilize all of the grouting material for filling the spaces, crevices and interstices between the stones, bricks or blocks.

- 5 To those skilled in the art of making devices of the class described, many alterations in construction and widely differing embodiments and applications of my invention will suggest themselves, without departing from the spirit and scope thereof. My disclosures and the description herein are purely illustrative and are not intended to be in any sense limiting.

What I claim is:

- 15 1. In a tool of the character described, the combination of a support comprising a pair of members, means for connecting said members together and maintaining them in parallel relationship with the space between them at all side edges of the members unobstructed, a section of continuous material arranged between said members and projecting therefrom along one longitudinal edge of said support, and a clamping device 20 arranged near the free longitudinal edge of one of said members and projecting therethrough into engagement with said section of material to adjustably secure it between the said members.
- 25 2. In a tool of the character described, the combination with a pair of separate spaced plates, means for holding the plates in their spaced relation with the space between the same unobstructed at all four edges comprising a plurality of narrow rigid spacing members fastened to the plates, a section of material adjustably secured between the plates and projecting beyond the lower edges thereof, devices passing through one

of said plates and engaging said section of material to hold it in its adjusted position, and a handle carried by one of the said plates.

3. In a tool of the character described, the combination with a pair of separate spaced plates a plurality of narrow rigid loop members connected to said plates and adapted to hold the plates in their spaced relation with the space between the same unobstructed at all four sides, a section of adjustable material located between said plates and projecting below the lower edges thereof, means for engaging and retaining said section of material in its adjusted position between the plates, and a handle carried by one of said plates.

4. In a tool of the character described, the combination with a pair of separate spaced plates, a plurality of narrow rigid loop members connected to said plates and having their upper ends extending beyond the plates and adapted to hold the plates in their spaced relation with the space between the same unobstructed at all four sides, a section of adjustable material located between said plates and projecting below the lower edges thereof, devices passing through one of said plates near the lower edge thereof and engaging said section of material to hold it in its adjusted position between the plates, and a handle carried by one of said plates.

In testimony whereof I affix my signature, in the presence of two witnesses.

JAS. G. BRICKER.

Copies of this patent may be obtained for five cents each, by addressing the "Commissioner of Patents, Washington, D. C."

It is hereby certified that in Letters Patent No. 1,306,135, granted June 10, 1919, upon the application of James G. Bricker, of Cleveland, Ohio, for an improvement in "Grouting-Tools," errors appear in the printed specification requiring correction as follows: Page 3, line 20, claim 1, after the word "them" insert the word *unobstructed*; same page and claim lines 20-21, strike out the word "unobstructed;" and that the said Letters Patent should be read with these corrections therein that the same may conform to the record of the case in the Patent Office.

Signed and sealed this 15th day of July, A. D., 1919.

[SEAL.]

R. F. WHITEHEAD,
Acting Commissioner of Patents.
